US00D869676S

(12) **United States Design Patent** (10) Patent No.: **US D869,676 S**
(45) Date of Patent: **** Dec. 10, 2019**

(54) **PARTICLE SORTING MODULE**

(71) Applicant: **Becton, Dickinson and Company**,
Franklin Lakes, NJ (US)

(72) Inventors: **Pierce O. Norton**, Los Gatos, CA (US);
Dennis F. Rey, Livermore, CA (US);
Jeannine K. Funderburk, Cupertino,
CA (US)

(73) Assignee: **Becton, Dickinson and Company**,
Franklin Lakes, NJ (US)

(**) Term: **15 Years**

(21) Appl. No.: **29/635,385**

(22) Filed: **Jan. 30, 2018**

CLAIM

The ornamental design for a particle sorting module, as shown and described.

DESCRIPTION

FIG. 1 is a front view of a particle sorting module;
FIG. 2 is a back view of the particle sorting module;
FIG. 3 is a first side view of the particle sorting module;
FIG. 4 is a second side view of the particle sorting module;
FIG. 5 is a top view of the particle sorting module;
FIG. 6 is a bottom view of the particle sorting module;
FIG. 7 is a back perspective view of the particle sorting module; and,
FIG. 8 is a front perspective view of the particle sorting module.

The broken lines illustrate portions of the particle sorting module that form no part of the claimed design; the broken lines form no part of the claimed design.

1 Claim, 7 Drawing Sheets
